UNITED STATES PATENT OFFICE.

PALMER W. REYNOLDS, OF BRONXVILLE, NEW YORK.

CONTROL CIRCUITS.

Application filed November 24, 1925. Serial No. 71,262.

This invention relates to control systems and more particularly to systems for controlling the operation of a valve.

The present invention is especially applicable to the heating of buildings wherein a heating medium is supplied to apparatus in the building through a pipe line under the control of a main valve. In such heating systems it has been found advisable to supply the heating medium to the apparatus intermittently in order that a temperature consistent with prevailing conditions can be maintained. Moreover these intervals of admission must be varied to correspond to variations in weather conditions.

Accordingly the present invention aims to provide in a system for controlling the operation of valve, means for intermittently opening and closing the valve, means for varying the intervals between the opening and closing of the valve, and means for rendering the intermittent opening and closing mechanism inactive while the valve is held open for a predetermined variable period.

Ancillary features incorporated in the system are the utilization of timing mechanism for causing the entire system to be automatic in operation, means for restoring all the elements of the system to an initial position at the end of each operating period, and means manually operated for turning the valve on or off and at the same time rendering a part of the system inactive.

In carrying out the invention, use is made of a balanced valve operated by a motor. A group of circularly arranged contacts, adapted to be bridged by a motor driven brush, are so associated with the valve motor through a series of variable switches that, the bridging of one set of contacts will cause the valve motor to be actuated in such a manner as to open or close the valve, dependent upon the setting of the above mentioned switch. A second series of contacts spaced apart outside the first contacts and adapted to be bridged by a second brush rotated simultaneously with the first brush, are so associated with the first set of contacts as to render them inactive for a predetermined variable period, during which time the valve is held open.

A main switch, which may be time controlled for causing the operation of the system to be automatic, governs the operation of the circuits for opening and closing the valve, while additional circuits are provided

for causing the brush carrying arm to rotate to its starting position and there be stopped regardless of its position at the time of opening of the main switch.

A more comprehensive understanding of the features and merits of the invention can be obtained by reference to the drawings wherein is illustrated a preferred embodiment of the same.

Referring to the drawings, A represents a valve preferably of the balanced type for controlling a suitable pipe line B. An operating valve arm 10 is raised or lowered by a chain 11 passing over pulleys 12 and actuated by a motor M¹. This motor is provided with a shaft 13 having an elbow to which one end of the chain 11 is attached so that as the shaft rotates the movement of the chain causes an up and down movement of the arm 10 to open and close the valve A respectively. Power for driving the motor is supplied by any convenient source as indicated by the lines 5.

The motor M¹ is provided with three control contacts 1, 2, 3, the contact 2 acting as a common contact for circuits to the other contact. Upon the closure of a circuit between the common contact and either one of the other contacts the shaft 13 is rotated thru an angle of 180° and then automatically stopped. The motor then remains inactive until a circuit is closed between the neutral and the other contact at which time the shaft will be further rotated through an angle of 180° and automatically stopped. Thus it may be seen, that as power is applied through one circuit and the shaft has completed its partial rotation and either opened or closed the valve, the circuits must be changed to cause the reverse operation of the valve.

In as much as the features and principles of operation of this type of motor and associated control is well known in the art, it is not described or illustrated in detail and no specific claim is made thereto.

In order that the valve may be opened and closed at predetermined intervals, and that these intervals may be varied to meet existent conditions a plurality of pairs of contacts 20 to 31 inclusive are spaced equidistant in the outline of a circle. One contact of each of the pairs 21-31 inclusive is connected directly to a bus 32 which, upon the energization of a relay R², is connected to the common contact 2 of the motor M¹.

through the normally open contacts C^1 . The remaining contacts of groups 21 and 27 are connected in parallel to a single pole double throw switch 33 by a conductor 34. 5 A similar switch 35 and conductor 36 serve the same purpose for contacts of groups 22 and 28; switch 37 and conductor 38 for groups 23 and 29, switch 39 and conductor 40 for groups 24 and 30, and switch 41 and 10 conductor 42 for groups 25 and 31. A conductor 43 in contact with a conductor 44 connects one contact of group 26 directly to the contact 1 on motor M^1 . A bus 45 has one end connected to the contact 3 on motor 15 M^1 through the lead 46. A similar bus 47 is connected to the contact 1 on motor M^1 through conductors 48 and 49, local contacts C^8 and conductor 44. Local contacts C^8 are closed only upon the energization of relay 20 R^8 . As shown the switches 33, 35, 37, 39 and 41 may be thrown to make contact with the bus 45 or 47 as may be desired.

For bridging the contact points of each of the groups 20 to 31 inclusive a motor M^2 is 25 adapted to rotate either directly or indirectly an arm 50 having a brush portion 51 and a second brush 53 the purpose of which will hereinafter be explained in detail. Insulating sections 52 and 54 prevent interference 30 between the brushes themselves and between the brushes and the arm 50. Power to operate motor M^2 is supplied from any convenient source, indicated by the lines 55, through the leads 56 and 57. The lead 57 35 is closed through the local contacts C^7 , which are opened only when relay R^7 is energized. Such energization takes place when the contacts of group 20 are closed, setting up a circuit from the lines 55 through the conductor 58, contacts 20 and conductor 59. A relay R^4 having local contacts C^4 is shunted across the line 59 for a purpose to be explained later.

Thus it may be seen that as the arm 50 45 rotates the contacts of the successive groups are closed and dependent upon the position of switches 33, 35, 37, 39 and 41 relative to the busses 45 and 47, circuits will be closed between the neutral 2 and one of the contacts 1 and 3 of motor M^1 .

For starting and stopping the operation of the system a master control switch 60 which may be controlled either manually or by a suitable timing mechanism D, is located 55 in the power lines 55. Upon the closure of switch 60 relay R^1 is energized through the circuit 61, 62, 63, 64, 65, 66, closing local contacts C^1 and placing a shunt across the line 57; relay R^8 is energized through circuit 61, 62, 63, 65, 66, closing local contacts C^8 , thereby completing a circuit 44, C^8 49, 48, 47, 67, C^6 , 68, 32, causing the motor M^1 to rotate in such a manner as to open the valve A. The contacts C^6 are held in a closed 65 position until relay R^6 is energized, in such

a manner permitting the completion of the last mentioned circuit. Simultaneously with the energization of relays R^1 and R^8 , relay R^6 is energized through the circuit 61, 69, 70, 71, 66 opening local contacts C^6 and 70 breaking a circuit 32, 72, 73, 46 which, being already established, had caused the motor M^1 to rotate in such a manner as to close the valve A.

In the heating of buildings it is desirable 75 that the heating medium be sometimes supplied to the apparatus in the building for a length of time at the beginning of the heating period to allow the building to warm up. Accordingly in the present invention means 80 are provided for rendering the intermittent control of the valve A inactive for predetermined lengths of time and also for holding the valve A open during such time.

These means comprise groups of contacts 85 75, 76, 77 one contact of each group being connected by the bus 78 to a line 79. One end of the line 79 terminates at a switch pole 80 while the remaining contacts of groups 75, 76 and 77 are connected to switch 90 poles 81, 82 and 83 respectively. A single pole switch 84 is adapted to make contact with any one of the switch points 80, 81, 82, or 83. Should the switch be set at point 80, the switch 60 having been closed, a circuit 61, 85, 86, switch 84, 79, 71, 66 will be closed, energizing relays R^6 and R^8 . Relay R^2 will also be energized through the circuit 61, 85, 86, switch 84, 79, 87, 64, 65, 63. Relay R^6 upon being energized opens the local contacts C^6 opening the previously described circuit between the common contact 2 and contact 1 on motor M^1 . Relay R^8 upon being energized closes the local contacts C^8 , thereby connecting the contact bus 32 with the common contact point 2 on motor M^1 . Relay R^2 upon being energized closes local contact C^2 , thereby closing a shunt across the lines 79 and 86, in such a manner locking the relays R^6 and R^8 in energized condition. 105

Should the switch 84 be in contact with either of the points 81, 82, 83, the relays R^2 , R^6 , and R^8 will be inactive until the arm 50 rotates sufficiently for the brush 53 to bridge 115 the contacts 75, 76, or 77, as the case may be, at which time the previously mentioned circuits will be closed in the same manner. Thus it will be seen that the contacts 21 and 31 inclusive have no effect on the operation 120 of the system until the local contacts C^8 are closed, connecting the bus 32 to the common contact 2 on the motor M^1 .

Suitable resistances 88 may be inserted in the lines 56, 57, 58, 59, 61, 66 to limit the power therein if so desired. 125

In order that the valve A may be opened or closed manually during the operation of the system a triple action switch 90 is provided. Switch 90 is composed of two sets 130

of contacts arranged in groups of two, with the members 91, 92 forming the upper group and the members 93, 94 forming the lower group. A resilient contact strip 95, is inserted between members 91 and 92, and a similar contact strip 96 is inserted between the members 93 and 94. A pivoted cam 97 having an operating lever 98 is so associated with the strips 95 and 96 as to hold them in substantially horizontal planes, when the lever 98 is in neutral position shown in the drawings. Members 91 and 92 are connected in the line 32 between the local contacts C⁸ and C⁶ and are both in contact with the strip 95 when the lever 98 is in neutral position. Strip 96 is connected directly to the line 32 and contacts 93 and 94 are connected to the lines 44 and 46 respectively, as shown. In neutral position neither of the members 93 and 94 contact with the strip 96.

Should the operator at any time desire to close the valve A, the lever 98 is pushed upwardly, rotating the cam 97 an amount sufficient to raise the strip 95 and member 91, thereby opening the line 32 and rendering the contacts 21-31 inclusive inactive during the rotation of brush arm 50. At the same time the resiliency of strip 96 forces it into contact with the member 93, closing a circuit 1, 93, 96, 32, 2, causing motor M¹ to operate, opening valve A. On the other hand, should it be desired that the valve be closed, the lever 98 is pushed downwardly, permitting the resiliency of strip 95 to force it and the member 92 downwardly, opening line 32, while the cam 97 forces strip 96 into contact with member 94, establishing a circuit 3, 94, 96, 32, 2, causing motor M¹ to close valve A.

In order that the valve A be opened when the switch 60 is closed, at the beginning of an operating period, means are provided for causing the motor M² to be stopped only when the contacts 20 are closed by the brush 51. The operation of such means is as follows:

At the time of opening of switch 60, should the contacts 20 be closed by the brush 50 the relay R⁷ would be energized through circuit 58, 20, 59, opening local contacts C⁷ and breaking the energizing circuit of the motor M² causing it to stop with the arm 50 in the position in which the brush 51 bridges contacts 20. On the other hand, should the arm 50 be at any position other than bridging contacts 20, at the time of opening of switch 60, motor M² will continue to rotate until the contacts 20 are closed, at which time it will be stopped in the manner explained before. Relay R⁴ is energized simultaneously with relay R⁷, closing contacts C⁴ so that a circuit may be closed between the points 1 and 2 upon resumption of operation.

In the operation of the system several

arbitrary conditions must first be determined and arrangements made therefor. For example, let it be assumed that the arm 50 is driven at such a rate as to complete one revolution every three hours. In such a case the contacts 20 to 31 inclusive will be spaced approximately 15 minutes apart. Next let it be assumed that the valve A is to remain open for fifteen minutes and closed for fifteen minutes. Accordingly the switches 33, 37, and 41 are thrown to make contact with the bus 45 while the switches 35 and 39 are thrown into contact with the bus 47. Inasmuch as the contacts 20 are the starting contacts and one of the contact 26 is connected to the contact 1, the valve A will always be opened when these pairs are bridged by the brush 51. Should it be desired that the intermittent opening and closing of the valve be started immediately, the switch 84 will be thrown into contact with the point 80. In this condition, i.e. starting position with the brush 51 bridging the contacts 20 and the switch 60 open, the relays R¹, R², R³, R⁵, R⁶ and R⁸ will be deenergized and the relays R⁴ and R⁷ will be energized.

At the desired time the switch 60 is closed either manually or automatically by the timing device D. Immediately relays R¹, R³ and R⁵ are energized simultaneously, closing local contacts C¹ and C³ and opening local contacts C⁵. The closing of contacts C¹ place a shunt across the line 57, closing a circuit 56, 57 to start the motor M² which drives the brush arm 50. The closing of contacts C³ establishes a circuit 32, 72, C⁴, 49, 44, starting the motor M¹ to open valve A. The opening of contacts C⁵ breaks a circuit 32, 72, 73, C⁵, 46 which had previously energized the motor M¹ to close the valve A, at the end of an operating period.

Simultaneously circuits are closed through the switch 84 to energize the relays R², R⁶, and R⁸, allowing the common contact 2 to be connected to the contact bus 32 through the contacts C⁸ and locking these relays in the manner before explained.

The brush arm 50 then rotates till the brush 51 closes contacts 21 at which time a circuit 46, 45, 33, 34, 21, 32 will be closed to start the motor M¹, closing the valve A. Further rotation of the brush arm 50 will cause the brush 51 to close contacts 22, establishing a circuit 32, 22, 36, 35, 47, 48, 49, C³, 44, to start the motor M¹, opening the valve. The bridging of contacts 23 and 25 closes circuits similar to that closed by contacts 21, while contacts 24 control a circuit similar to that controlled by contacts 22.

When the brush arm rotates sufficiently for the brush 51 to bridge contacts 26 a circuit 44, 43, 32 is established opening the valve A. This action is definite and occurs regardless of the setting of the switches

33, 35, 37, 39 and 41. Inasmuch as the groups 21, 22, 23, 24 and 25 are connected in parallel with groups 27, 28, 29, 30 and 31 respectively the bridging of the last mentioned groups closes circuits identical with those of the first mentioned group with which they are associated.

This intermittent opening and closing of the valve A continues till at a desired time the switch 60 is opened either automatically by the time device D or manually, whereupon the relays R¹, R², R³, R⁵, R⁶ and R⁸ are deenergized, opening local contacts C¹, C², C³ and C⁸ and closing local contacts C⁵ and C⁶. The opening of contacts C¹ breaks the shunt across the line 57 and leaves the power supplied to the motor M² under the control of relay R⁷. The opening of contacts C² removes the energizing lock from the relays R⁶ and R⁸ and permits them to remain inactive. The opening of contacts C³ opens the circuit to the common contacts 2 of motor M¹, preventing a circuit between contacts 2 and 1 from being closed. The closing of contacts C⁵ sets up a circuit 32, 72, 73, C⁵, 46, starting the motor M¹ to close the valve A. The closing of contacts C⁶ places the valve opening circuit in readiness for resumption of operation, while the opening of contacts C⁸ breaks the connection between the contact bus 32 and the common contact 2 of motor M¹ rendering the contacts 21-31 inclusive inactive.

Should the contacts 20 be bridged by brush 51 at the time of opening of the switch 60, the motor M² is immediately stopped, otherwise it will continue running until those contacts are closed at which time it will be stopped in the manner hereinbefore explained.

Should conditions prevail which render it desirable for the valve A to be allowed to remain open for considerable period, for example an hour, an hour and a half, or two hours, at the beginning of a heating period, the switch 84 would be turned to make contact with the points 81, 82 or 83 respectively. With the closing of switch 60, the relays R¹, R³ and R⁵ would be energized as before explained but the relays R², R⁶ and R⁸ would not be energized until the arm 50 had rotated an amount sufficient for the brush 53 to bridge the contacts 81, 82 or 83 as the case might be. Until that time the circularly arranged contacts would be inactive. However, upon the bridging of the contacts 81, 82 or 83 by the brush 53, the relays R², R⁶ and R⁸ would be energized and the operation would continue as before explained.

It is to be understood that the timing of the system is arbitrary and that the intervals mentioned herein are cited merely as examples, the actual setting and arrangement of the various parts being capable of

adjustment to meet varying circumstances. Moreover the intermittent opening and closing of the valve can be carried within the range determined by the speed of rotation of brush 50 by varying the setting of switches 33, 35, 37, 39 and 41.

Thus it will be seen that the present invention provides decided advantages over existent systems and that it produces a distinct advancement in the art. Once started the intermittent opening and closing of the valve continues until the main switch is opened. Should the timing mechanism D fail after the system is in operation, the system will function properly until the mechanism is repaired or the main switch closed manually.

It is further to be understood that the present invention is not to be limited by the scope of the illustrated embodiment, but only by the scope of the appended claims.

What is claimed is:

1. In a control system the combination with a motor-operated valve, of a main switch, means whereby the closing of said switch causes said motor to open said valve, means for intermittently causing said motor to close and open said valve after the closing of said switch, and means whereby the opening of said switch causes said motor to close said valve and stops the intermittent closing and opening thereof.

2. In a control system the combination of a valve, a control switch, motor driven means for causing the intermittent opening and closing of said valve, means for automatically causing the opening of said valve upon the closure of said switch, and means for simultaneously energizing said motor driven means.

3. In a system in accordance with claim 2, means for automatically causing the closure of said valve upon the opening of said switch and means for simultaneously stopping the intermittent opening and closing of said valve.

4. In a control system the combination with a motor-operated valve, of motor driven mechanism for intermittently energizing said motor to open and close said valve, means for causing said valve to remain open for a predetermined period, means for rendering said mechanism inactive during said period without stopping the motor driving said mechanism, and means for automatically rendering said mechanism active at the end of said period.

5. In a control system the combination of a valve, separately driven means for causing the intermittent opening and closing said valve and manually operated means for causing the opening or closing of said valve and for simultaneously rendering said driven means inactive without stopping the driving thereof.

6. In a control system the combination of a valve, a motor for operating said valve, a control switch, separately driven means for energizing said motor at intervals to open and close said valves, means for automatically causing the actuation of said driven means upon the closing of said switch, and means for automatically causing said driven means to return to its starting point after the opening of said switch.
7. In a control system the combination with a motor-operated valve, of a control switch, separately driven means for intermittently energizing said motor to open and close said valve at predetermined variable intervals, means for automatically energizing said motor to open the valve upon the closure of said switch and for simultaneously actuating said driven means, means for causing said valve to be held open for a predetermined variable period and for rendering said driven means inactive during said period, means for rendering said driven means active at the end of said period, means for causing said motor to close said valve and for automatically rendering said driven means inactive upon the opening of said switch, and means for causing said driven means to return to its starting point and to be automatically stopped after the opening of said switch.
8. In a system in accordance with claim 7, manually operated means for causing said motor to operate said valve and for simultaneously rendering said driven means inactive.
9. In a control system, the combination of a valve, a motor for operating said valve, separately driven means for intermittently energizing said motor at predetermined intervals to cause positive opening of said valve and for causing intermittent opening and closing of the valve during the periods between said intervals.
10. In a control system, the combination with a motor-operated valve, of a plurality of contact points, electrically connected to said motor, means for closing circuits through said contact points to cause energization of said motor for opening and closing said valve, and means for varying the circuits associated with each of said contact points whereby the opening and closing of said valve is varied.
11. In a control system, the combination with a motor-operated valve of a plurality of electric circuits associated with said motor, means for successively closing said circuits for operating the motor to open and close said valve, and means for rendering the closing of certain of said circuits ineffective upon the actuation of said motor whereby the periods between the opening and closing of the valve may be varied.
12. In a control system, the combination of a valve, a control switch, means for operating said valve, driven means for causing the actuation of said operating means to open and close said valve according to a predetermined cycle, means for automatically energizing said driven means upon the closing of said switch, and means for causing said driven means to complete its cycle regardless of the position thereof at the time of opening of said switch.
13. In a control system, the combination of a valve, a control switch, means for automatically causing the opening of said valve upon the closure of said switch, means for causing the intermittent opening and closing of said valve during the period of closure of said switch, and means for automatically causing the closing of said valve upon the opening of said switch and for causing said valve to remain closed until said switch is closed.
14. In a control system, the combination of a valve, a motor for operating said valve, a control switch, separately-driven means for causing the energization of said motor at intervals to open and close said switch, means for automatically causing said motor to open said valve upon the closure of said switch, means for simultaneously causing the actuation of said driven means, means for rendering said driven means inactive without stopping the driving thereof for a predetermined period after the closure of said switch, and means for automatically rendering said driven means active at the expiration of said period.

In testimony whereof, I have signed my name to this specification.

PALMER W. REYNOLDS.
